ABSTRACT

A shelf system is shown and described. A post has an aperture. A pin is configured to extend through that aperture. The pin has a head having a first circumference and a body having a second circumference. A collar is configured to encircle the post and rest on the pin head and body. In operation the collar, and any associated shelf, is able to rotate smoothly and stably around the post.

1
ROTARY SHELF SYSTEM

This application claims the invention disclosed in provisional application Ser. No. 60/775,717, filed on Feb. 23, 2006.

FIELD

The present invention relates to a rotary shelf construction and assembly and, more particularly, to a fixed-post rotary shelf construction and assembly. Even more particularly, the present invention relates to improving the rotation and stability of fixed-post rotary shelf systems.

RELATED ART

Corner cabinets, e.g., corner kitchen cabinets, are common features in most houses or businesses. These cabinets offer significant storage space that is commonly difficult to access because of the depth or shape of the cabinet. Rotary shelving or "Lazy Susan" type shelving is often utilized to enhance access to the space contained within corner cabinets. Rotary shelves typically come in two types, rotating-post types and fixed-post types. With rotating-post types of rotary shelves, the shelf is fixedly attached to the rotating post to achieve shelf rotation within the cabinet. With fixed-post types of rotary shelves, the shelf is allowed to rotate around the fixed post to achieve shelf rotation. Each of these types of rotary shelves also commonly has a desired rest-position for the shelf. For example, a rest-position may be a position along the rotation of the shelf that is somewhat resistant to rotation and used to maintain the shelf at a particular location. Rest-positions are desirable, for example, for proper cabinet door positioning or simply to allow for a reference point for positioning or locating items on a shelf.

The fixed-post type of rotary shelf has historically had drawbacks. For example, they are either unable to rotate a full 360 degrees smoothly or without a bump at 180 degrees from the rest-position, or they are unable to adequately distribute the load of the shelf. Some, for example, in an effort to distribute the load of the shelf evenly, have constructed shelves that rotate on dual contact points. With this type of construction, shelves have a desired first rest-position, e.g., at 0 degrees, and an undesirable second rest-position or bump, e.g., at 180 degrees. This second "bump" disrupts operation and can cause items stored on shelves to topple during rotation. To address this problem, others have constructed shelves that rotate on a single contact point, which allows for only a single rest-position. These shelves, however, fail to evenly distribute the shelf load on both sides of the post, and thus lead to an unstable or un-level shelf.

It is to these, and other, problems that the present invention is directed.

SUMMARY

An object of the present invention is, therefore, to provide a rotary shelf that can rotate a full 360 degrees with only a single rest-position;

Another object of the present invention is to provide a rotary shelf that rotates smoothly and in a substantially level position;

Still another object of the present invention is to provide a rotary shelf that rotates on dual contact points;

A further object of the present invention is to provide a fixed-post type of rotary shelf that rotates on dual contact points and that can rotate a full 360 degrees with only a single rest-position;

2

Still another object of the present invention is to provide a rotary shelf system that is easy to manufacture and install.

To summarize, one embodiment of the invention includes a shelf system for use with a post having an aperture. The system includes a pin having a head having a first circumference, and a body having a second circumference smaller than the first circumference. The body of the pin includes a portion configured to extend through the aperture of the post. The system also includes a collar configured to encircle the post and rest on the pin head and on the portion of the pin body extended through the post.

Certain embodiments of the invention are set forth in more detail below.

15 BRIEF SUMMARY OF THE DRAWINGS

FIG. 1 is an exploded perspective view of one embodiment of the shelf system of the present invention;

FIG. 2 is a partially exploded perspective view of the system shown in FIG. 1;

FIG. 3 is a close-up exploded perspective view of part of the system shown in FIG. 1;

FIG. 4 is another close-up exploded perspective view of part of the system shown in FIG. 1;

FIG. 5 is a close-up perspective view of the underneath side of the collar shown in FIG. 1;

FIG. 6 is a close-up perspective view of the pin shown in FIG. 1;

FIG. 7 is a close-up perspective view of a collar resting on a pin inserted into a post;

FIG. 8 is another close-up perspective view of a collar resting on a pin inserted into a post;

FIG. 9 is a close-up perspective view of the top of the collar shown in FIG. 1;

FIG. 10 is a close-up perspective view of a shelf including a shelf hub; and

FIG. 11 is a close-up perspective view of another embodiment of a pin.

40 DETAILED DESCRIPTION OF THE DRAWINGS

FIGS. 1 and 2 show perspective views of one embodiment of a fixed-post type of rotary shelf. Rotary shelf 1 includes a base plate 4 configured to be mounted to the floor of a cabinet 45 through mounting apertures 4a defined by base plate 4. Post 12 is fixedly mounted to base plate 4. A pair of shelf systems 2a and 2b are also shown. FIG. 1 shows systems 2a and 2b as exploded along post 12, while FIG. 2 only shows system 2b as exploded. As seen, system 2 includes shelf hub 10 (shelf surface not shown to facilitate illustration of other components), collar 16, and pin 18. In some embodiments, the shelf system may also be considered to include post 12.

In terms of assembly, post 12 may be mounted to a cabinet (not shown) through mounting plate 4. Pin 18 may be inserted 55 into an aperture (see FIG. 3), and be secured simply by its own design. Collar 16 may be inserted into shelf hub 10, and the combination may be inserted onto post 12. Alternatively, collar 16 may be placed on post 12 and shelf hub 10 may be lowered down post 12 to engage collar 16. After assembly, the shelf system will rest on pin 18 and resemble system 2a as shown in FIG. 2. Those of ordinary skill will recognize that mounting plate 4 will preferably be mounted to the interior floor of a cabinet, yet other embodiments of the present invention will work equally as well if mounting plate 4 is mounted, 60 for example, to the interior top of the cabinet. Additionally, while one of the benefits of the present invention is its ability to operate smoothly with only one mounting plate, those of

ordinary skill in the art will recognize that other embodiments may use two mounting plates, e.g., a plate to attach to the internal floor of a cabinet and a plate to attach to the internal top of a cabinet.

FIGS. 3 and 4 show close-up perspective views of shelf system 2. Shelf hub 10 is slidably and rotatably positionable on post 12 and defines recess 14 configured to receive and engage collar 16. Collar 16 is slidably and rotatably configured to encircle post 12, and is further configured to mount within recess 14 of hub 10. While collar 16 is shown as separate from shelf hub 10, those of ordinary skill in the art will recognize that collar 16 could be integral with shelf hub 10.

Pin 18 is configured to extend through aperture 12a of post 12. Pin 18 has head 22, body 24, and body portion 24a, which extends through post 12. In this embodiment, pin 18 is configured to be self-securing by, for example, having at least one wing 26, and preferably, as shown, a pair of wings 26. Applicants have found that single wing embodiments can be self securing and provide some level of stability. These embodiments may, however, be difficult to insert into the aperture because torque generated by the single wing may disrupt the motion of the pin as it moves within the aperture. Applicants prefer a pair of wings because they have discovered that a pair of wings provides greater reduction of pin rotation within the post, provides greater stability during the rotation of the shelf, and allows for easy pin insertion into the post. Wings 26 attach at one end to pin 18 near or on head 22. Wings 26 engage post 12, for example, by being shaped to at least partially encircle post 12 when pin 18 is fully received by post 12. The flexing nature of wings 26 may further secure pin 18 frictionally to post 12.

In other embodiments, others may prefer non-self securing pins or may wish to secure their pins in other ways, or use a pin made of multiple parts. For example, some may desire to thread a pin head into a threaded aperture on one side of the post and thread a separate pin body portion onto another hole on the opposite side of the post or at another location on the post. Such embodiments are considered to be within the scope of the present invention.

Collar 16 is configured to rest on head 22 and portion 24a of pin 18, preferably in a substantially level position, and even more preferably in an essentially level position. FIG. 5 shows a close-up perspective view of the bottom or underneath side of collar 16, and FIG. 6 shows a close-up perspective view of pin 18. As shown, collar 16 is substantially annularly shaped and includes an inner portion 16a configured to engage head 22 of pin 18, and outer rim 16b offset from inner portion 16a and configured to engage portion 24a of pin 18. Preferably, inner portion 16a includes an inner indent 17a, and outer rim 16b includes an outer indent 17b. Preferably, inner indent 17a is configured to engage head 22, and outer indent 17b is configured to engage portion 24a of pin 18. In the present embodiment, the outer indent is substantially opposite of the inner indent and is offset from the inner indent. As mentioned, the portion configured to engage the pin head is an inner portion of the collar, yet others may prefer other configurations. For example, others may prefer a collar having an inner portion configured to engage pin portion 24a and an outer portion configured to engage the pin head. Further, inner and outer indents, in some embodiments need not be positioned substantially opposite each other. The positioning of the indents may depend, for example, on the type, shape, or number of components of the pin used. All such variations are considered to be within the scope of the present invention.

The combination of inner indent 17a, outer indent 17b, and the configuration of pin head 22 and body 24a allow for a

single rest-position for hub 16 as shown in FIGS. 7 and 8. From the rest-position shown in FIGS. 7 and 8, collar 16 supported by pin 18 (and any attached shelf) can rotate around post 12 a full 360 degrees and return to the displayed rest-position without encountering a second rest-position or bump. Preferably collar 16 is supported at two points during substantially the entire rotation, and the entire rotation from the rest position is smooth, stable and level. Further, through the configuration of inner and outer indents, entry into the rest position and exit from the rest position are both smooth and stable.

Referring back to FIG. 5, inner indent 17a has a first slope ma and outer indent 17b has a second slope mb. In the present embodiment, the two slopes are configured to allow collar 16 to smoothly and evenly exit, and return to, the rest position (e.g., as shown in FIG. 7). Slopes of the indents may be different and may be selected, for example, to account for the difference in circumference of head 22 and pin portion 24a. First and second slopes are preferably selected to allow hub 16 to move into and out of the rest position (e.g., as shown in FIG. 7) with one uniform and level motion. For example, collar may lower or rotate into the rest position by allowing inner indent 17a to receive head 22 of pin 18, which has a first circumference, at substantially the same time outer indent 17b receives portion 24a of pin 18, which has a smaller circumference. Those of ordinary skill in the art will recognize that slopes and indent depth may be varied, for example, depending on the various circumferences of pins used or depending on the desired stability of the rest position or amount of force required to rotate out of the rest position. All such variations are considered to be within the scope of the present invention.

FIG. 9 shows a close-up perspective view of the top of collar 16 of the present invention. Collar 16 includes various slots 30 defined in the collar or top surface of the collar. FIG. 10 shows a perspective view of an underside portion of shelf 40 of the present invention. Shelf 40 includes shelf hub 10 (illustrated previously in FIGS. 1 and 2) having recess 14 configured to receive and engage collar 16. Fingers 14a are positioned within recess 14 and configured to engage slots 30 located on the top surface of collar 16. In some embodiments, it may be preferable to position slots and fingers at irregular intervals or by staggering, such that collar 16 will only engage hub 10 in one orientation. In other embodiments, such positioning may not be desired. Further, while applicants prefer to construct the shelf and collar as separate pieces for reasons relating to molding and shipping, those of ordinary skill in the art will recognize that they could be a single piece within the context of the present invention.

FIG. 11 shows another embodiment of a pin 118 of the present invention. In this embodiment, pin head 122 includes a roller 122a configured to rotate with respect to pin body 124. Wings 126 are fixedly attached at one end to body 124 and prevent pin-body rotation when pin 118 is inserted into the post. Portion of body 124a also includes another roller 124b, which is also configured to rotate with respect to pin body 124. Some may prefer rollers to reduce friction between the pin and the collar of the present invention. While two rollers are shown, those of ordinary skill in the art will recognize that other embodiments of the present invention may include either roller 122a or roller 124b.

From the preceding description, it can be seen that the present invention provides a system that meets all the advantages of related systems and offers additional advantages not heretofore achievable. With respect to the foregoing invention, the optimum dimensional relationship to the parts of the invention including variations in size, materials, shape, form,

5

function, and manner of operation, use and assembly are deemed readily apparent to those skilled in the art, and all equivalent relationships illustrated in the drawings and described in the specification are intended to be encompassed herein.

The foregoing is considered as illustrative only of certain embodiments of the present invention. Numerous modifications and changes will readily occur to those skilled in the art, and it is not desired to limit the invention to the exact construction and operation shown and described. The present invention is intended to be limited only by the broad scope of the appended claims.

What is claimed is:

1. A shelf system for use with a post having an aperture, 15
said system comprising: a pin having
a head having a first circumference, and
a body having a second circumference smaller than said
first circumference, said body including a portion con-
figured to extend through said aperture of said post; and
a collar configured to encircle said post and rest on said pin
head having said first circumference and on said portion
of said pin body extended through said post having said
second smaller circumference, and wherein said collar
includes
an inner portion configured to engage said head of said
pin, and
a rim offset from said inner portion and configured to
engage said portion of said pin extended through said
post.
2. The system of claim 1, wherein said rim of said collar is
an outer rim surrounding said inner portion.
3. The system of claim 2, wherein said inner portion of said
collar includes an inner indent, and wherein said outer rim
includes an outer indent.
4. The system of claim 3, wherein said inner indent and said
outer indent are configured to create a single rest position for
said collar, and wherein the remainder of said outer rim and
said inner portion is substantially flat, thereby allowing said
collar to rotate around said post 360 degrees and return to said
single rest position without encountering a second rest-position.
5. The system of claim 3, wherein said outer indent is offset
from said inner indent.
6. The system of claim 3, wherein said outer indent is 45
substantially opposite said inner indent.
7. The system of claim 3, wherein said inner indent is
configured to engage said head of said pin, and where said
outer indent is configured to engage said portion of said pin
extended through said post.
8. The system of claim 7, wherein said inner indent has a
first slope and said outer indent has a second slope, wherein
said first slope and said second slope are configured to allow
said inner indent to rest on said head having said first circum-
ference as said outer indent rests on said portion of said pin
body extending through said post having said smaller circum-
ference, thereby allowing for smooth and even force distri-
bution as said collar rotates into and out of said rest position.
9. The system of claim 1, wherein said portion of said pin
configured to extend through said aperture of said post
includes a roller.
10. A shelf system for use with a post having an aperture, 55
said system comprising: a pin having
a head having a first circumference, and
a body having a second circumference smaller than said
first circumference, said body including a portion con-
figured to extend through said aperture of said post; and
a collar configured to encircle said post and rest on said pin
head having said first circumference and on said portion
of said pin body extended through said post having said
second smaller circumference, and wherein said pin
includes at least one wing being configured to engage
said post in a self-securing manner.

6

11. The system of claim 10, wherein said pin head includes
a roller.

12. A shelf system for use with a post having an aperture, 10
said system comprising: a pin having
a head having a first circumference, and
a body having a second circumference smaller than said
first circumference, said body including a portion con-
figured to extend through said aperture of said post; and
a collar configured to encircle said post and rest on said pin
head having said first circumference and on said portion
of said pin body extended through said post having said
second smaller circumference, and wherein said pin
includes a pair of wings attached to said pin at one end
near said head of said pin, wherein said pair of wings are
positioned on substantially opposite sides of said pin,
thereby substantially reducing pin rotation within said
post and increasing stability of said system.

13. A shelf system for use with a post having an aperture, 25
said system comprising:
a pin having

a head having a first circumference, and
a body having a second circumference smaller than said
first circumference, said body including a portion con-
figured to extend through said aperture of said
post: and

a collar configured to encircle said post and rest substan-
tially evenly on said pin head having said first circum-
ference and on said portion of said pin body extended
through said post having said second smaller circum-
ference, said collar including
an inner portion configured to engage said head of said
pin,

an outer rim offset from said inner portion and config-
ured to engage said portion of said pin extended
through said post,

an inner indent defined by said inner portion of said
collar, and

an outer indent defined by said outer rim and being offset
from said inner indent and positioned substantially
opposite said inner indent, thereby creating a single
rest position.

14. The system of claim 13, wherein said inner indent is
configured to engage said head of said pin, and where said
outer indent is configured to engage said portion of said pin
extended through said post.

15. The system of claim 14, wherein said inner indent has
55 a first slope and said outer indent has a second slope, wherein
said first slope and said second slope are configured to allow
said inner indent to rest on said head having said first circum-
ference as said outer indent rests on said portion of said pin
body extending through said post having said smaller circum-
ference, thereby allowing for smooth and even force distri-
bution as said collar rotates into and out of said rest position.

16. The system of claim 13, wherein said pin includes at
least one wing configured to engage said post in a self-securing
manner.

17. A shelf system comprising:
a post attached to a mounting plate, said post defining at
least one aperture;

a pin having
a head having a first circumference and being configured
to be positioned on one side of said post, and
a body having a second circumference and including a
portion configured to be positioned on another side of
said post; and
a collar configured to encircle said post and rest substan-
tially levelly on said pin head having said first circum-
ference and on said portion of said pin body positioned
on another side of said post having said second circum-
ference, and wherein said collar includes
an inner portion configured to engage said head of said
pin, and

an outer rim offset from said inner portion and config-
ured to engage said portion of said pin on another side
of said post.

18. The system of claim 17, wherein said inner portion of
said collar includes an inner indent and said outer rim
includes an outer indent, and wherein the remainder of said
outer rim and said inner portion is substantially flat,
thereby allowing said collar to rotate around said post 360
degrees and return to said single rest position without
encountering a second rest-position.

* * * * *
